UNITED STATES PATENT OFFICE

106,833

DESIGN FOR A DISPLAY STAND

Carl E. Lehman, Chicago, Ill.

Application December 1, 1936, Serial No. 66,242

Term of patent 7 years

To all whom it may concern:

Be it known that Carl E. Lehman, a citizen of the United States of America, residing at Chicago, in the county of Cook and State of Illinois, has invented a new, original, and ornamental Design for a Display Stand, of which the following is a specification; reference being had to the accompanying drawing, forming part thereof:

Fig. 1 is a front elevational view of the display stand, showing my design.

Fig. 2 is a rear view of the display stand.

The dominant feature of the instant design consists in a circular front face having a marginal narrow strip projecting from the upper portion of the periphery thereof and in the same plane with said face, said strip being of contrasting color with the latter. The circular face is supported by a base having an inner narrow rectangular colored border adjacent the bottom edge thereof, all as shown.

I claim:

The ornamental design for a display stand as shown and described.

CARL E. LEHMAN.
